UNITED STATES PATENT OFFICE

HENRY M. RUNDLE, OF GLEN RIDGE, NEW JERSEY

DESIGN FOR A COMBINED DOLL OR SIMILAR ARTICLE AND SUPPORT FOR SAME

Application filed April 30, 1932. Serial No. 43,666. Term of patent 14 years.

To all whom it may concern:

Be it known that I, HENRY M. RUNDLE, a citizen of the United States, residing at #1 Spencer Road, Glen Ridge, county of Essex, State of New Jersey, have invented a new, original, and ornamental Design for a Combined Doll or Similar Article and Support for Same, of which the following is a specification, reference being had to the accompanying drawing, forming part thereof, in which—

Fig. 1 is a front elevational view of a combined doll or similar article and support for same embodying my new design; and
Fig. 2 is a perspective view thereof.

I claim:

The ornamental design for a combined doll or similar article and support for same, substantially as shown.

HENRY M. RUNDLE.
